UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,308,594.

Specification of Letters Patent.

Patented July 1, 1919.

Original application filed September 28, 1915, Serial No. 52,999. Divided and this application filed November 21, 1916. Serial No. 132,540.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawings, and being a division 10 of application Serial No. 52,999, filed by me September 28th, 1915.

My invention relates to typographical machines, such as linotype machines of the general organization represented in U. S. Letters Patent to O. Mergenthaler, No. 436,532, 15 wherein circulation matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing 20 mechanism to the magazine from which they started. More particularly, it relates to machines equipped with a plurality of magazines containing matrices of different style 25 or font, any selected one of which may be brought into action at will.

My present invention is directed to various improvements in the distributing devices of such machines which will be fully pointed out in the detailed description to 35 follow. In the accompanying drawings, I have shown my improvements merely in preferred form and by way of example, and obviously many changes and variations may be made therein and in their mode of application which will still be comprised within the spirit of my invention. Generally speaking, I desire it to be understood that I do not limit myself to any specific form of embodiment, except in so far as such limitations are specified in the claims.

Referring to the drawings:

Figure 1 is a side elevation of a portion of a linotype machine having my improvements applied thereto;

50 Fig. 2 is a side elevation taken at the

upper ends of the magazines and showing the distributing mechanism swung upwardly out of operative position;

Fig. 2^a is a rear elevation, partly broken away, of the parts shown in Fig. 2; 55

Fig. 3 is a rear elevation of the font separator and part of the distributing mechanism;

Fig. 4 is an end view of the parts shown in Fig. 3 with the distributor mechanism in 60 raised position;

Fig. 5 is a detail of the distributor-driving clutch; and

Fig. 6 illustrates a modification.

The matrices X are stored according to 65 font in one or the other of the magazines B, only two of which are shown herein, but of which a greater number might be employed if desired. The matrices are released from their corresponding magazines and composed in line in the usual way, and then presented to the casting mechanism for the production of the slug or linotype. After the casting operation, the matrices are carried upward and delivered to the front separator E, which assorts them according to 70 font and drops them into one or the other of the tubes E¹ leading to the distributing mechanism E² whereby they are separated 75 according to character and returned through 80 the channel entrances F to the proper channels of the magazine from which they started. The foregoing parts, except as herein-after pointed out, are or may be of any appropriate or well-known construction, 85 such as that employed in the commercial "Model 9" linotype, or as illustrated in the Rogers U. S. Patent No. 848,771.

The distributing mechanism E² comprises 90 two longitudinal bars E³ of the usual construction, one for each magazine, a set of conveying screws E⁴ for propelling the matrices therewith, and distributor boxes E⁵ into which the matrices are discharged 95 from the delivery tubes E¹ leading from the font separator E and which feed them onto the respective bars E³, one by one, in the usual way. The screws E⁴ are connected together, so as to operate in unison, by gearing E¹⁴ driven by gears M fixed to the operating 100

shaft M^1 receiving motion through a friction clutch from the constantly driven pulley M^2 loosely mounted on the shaft. The connecting clutch herein shown is substantially 5 the same as that disclosed in the Rogers Patent No. 1,088,984, comprising two relatively movable sections M^3 and M^4 (see Figs. 2^a and 5) provided respectively with connecting elements M^5 which are normally 10 held in engagement by a spring M^7 . When the elements M^5 are so engaged the clutch is operatively connected with the driving pulley M^2 , but when such elements are disengaged, as by the arrest of one of the distributor screws, the section M^3 is moved out 15 of engagement with the driving pulley M^2 and thus effects the arrest of the distributing mechanism. All these parts and their manner of operation are fully set forth in the 20 Rogers patent and require no further explanation here. It should be noted, however, that in the present instance the resetting of the clutch after its disconnection is effected by means of a lever M^9 pivoted between its 25 ends to the framework and provided at its upper end with a pin engaging in a grooved collar M^8 on the end of the clutch section M^4 .

As shown clearly in Fig. 2, both the distributing mechanism and the channel entrances F are mounted on swinging frames so that they may be moved from their operative position to give access to the magazines or the interior parts. The channel entrances F are carried in the usual way by a supporting frame F^1 which is pivotally connected to the machine frame, as at F^2 , so as to be swung downwardly away from the magazines as indicated by dotted lines in 40 Fig. 2. The two distributor bars E^3 (Fig. 6) are attached to a pair of overlying supporting brackets E^6 secured to the outer ends of arms E^7 which are pivotally mounted upon a transverse rod E^{10} of the framework, and have short extensions E^8 carrying set screws E^9 adapted to engage with fixed abutments e^9 arranged at opposite sides of the framework and hold the parts in proper position. The conveying screws 45 E^4 are journaled in supporting plates E^{11} attached to the opposite ends of the distributor bars E^3 , the plates at the left also giving support to the distributor boxes E^5 . (See Fig. 3.) The whole of the distributing 50 mechanism is thus mounted to be swung upwardly from its operative position about the rod E^{10} ; and in order that the initial movement of the supporting frame may be directly upward away from the underlying 55 channel entrances and in the direction of the length of the matrices passing to the latter from the distributing mechanism, the pivot rod is located below the horizontal plane of the distributor bars, as distinguished from above them, as in prior con-

structions. The purpose of this arrangement is to prevent the engagement with the channel entrances of any matrices which should be hanging on the distributor bars at the time they are swung upward. 70

The swinging of the distributing mechanism just described is effected by means of a hand lever K^2 fixed to a rock shaft K^1 suitably journaled in the framework and provided at its inner end with a cam K co-operating with a roller E^{13} secured to a depending arm E^{12} of the supporting plate E^{11} at the right. By shifting the hand lever K^2 , therefore, from and to its normal position (which is a horizontal one, as shown 80 in Fig. 1), the distributing mechanism is raised and lowered from and to its operative position, the upward movement thereof being limited by the engagement of pins K^{11} and K^{12} fixed to the hand lever and framework respectively, and the downward movement limited by the set screws E^9 before referred to. 85

In order that the font separator tubes E^1 will offer no obstruction to the upward 90 movement of the distributing mechanism, they are pivoted between their ends upon a horizontal fore and aft stud e so as to rock or tilt freely thereon. As a result of this construction, when the distributing mechanism is swung upward, its supporting plate E^{11} at the left will engage the tubes and shift them to the position shown by dotted lines in Fig. 3 and by full lines in Fig. 4, it being noted that the plate is beveled or 95 cut away at the rear as at e^5 to avoid an excessive rocking of the tubes. If desired, the plate E^{11} may be provided at one side with a projecting plate e^3 to engage a screw head or roller e^2 on one of the separator 100 tubes to provide clearance between the parts. The pivotal point of the tubes is so located that they will return to their normal position as the distributing mechanism is lowered, but if desired a weight e^4 may be applied to their lower ends to insure such return. To permit the ready removal of the tubes E^1 , their pivot stud e is detachably mounted in the framework as by a pin e^1 105 engaging in a peripheral groove in the stud 110 (see Fig. 4).

Fig. 6 illustrates an alternative construction wherein the separating tubes E^1 , instead of being rocked by engagement with the distributor frame, are connected to the hand lever K^2 , so as to be controlled more directly thereby. Here, it will be seen that the shaft K^1 is provided at its inner end with a crank arm K^9 connected by a pin and slot connection to a crank arm N^1 fast to one end of a 115 shaft N , passing through the before mentioned rod E^{10} (which, more properly speaking, is in the form of two sleeves for that purpose, as shown in Fig. 6), the opposite end of the shaft having a crank arm N^2 con- 130

nected by a link N^3 to a lever N^4 pivoted at one end to the framework and having its opposite end arranged in engagement with an angle-plate e^6 on the side of one of the 5 separator tubes. It follows from this construction that the depression of the hand lever K^2 to raise the distributing mechanism will, through the connections described, effect the upward rocking or tilting of the 10 tubes E^1 . In order that such tilting of the tubes may precede the upward movement of the distributing mechanism the cam K is provided with a concentric portion K^a whereon the roller E^{13} of the distributor 15 plate E^{11} rests a short distance away from the cam surface, so that the initial movement of the hand lever K^2 will rock the tubes upwardly a slight extent without disturbing the normal position of the distributing 20 mechanism.

The initial movement of the hand lever K^2 just described is also relied upon to disengage certain locking means which are provided to hold the distributing mechanism 25 against upward movement. Such locking means, in the present instance, consist of a spring-actuated double-hooked pawl O pivoted to the rearward extension E^8 of one of the arms E^7 of the distributor frame, 30 and having one of its hooks in engagement with a pin O^1 on the fixed framework and the other with a pin projecting laterally from an arm N^5 fixed to the shaft N , the arrangement being such that the rotation of 35 the shaft N by the operation of the hand lever K^2 disengages the arm N^5 from the pawl, which then under the action of its spring moves out of engagement with the pin O^1 , so that the distributing mechanism 40 is free to be swung upward. According to this arrangement, therefore, if any matrices should become lodged between the separator tubes E^1 and the distributor boxes E^5 , the rocking of the tubes is resisted, and consequently 45 the raising of the distributing mechanism is prevented, until the obstruction is removed, thus avoiding injury to the parts. In order to relieve the parts of strain in the event of such resistance, the crank arm K^9 50 is connected to the shaft K^1 by a spring K^{10} which permits it to yield.

Fig. 6 also illustrates a modified form of support for the font separator tube E^1 , it being noted therein that the stud e shown 55 in Fig. 4 has been replaced by a sliding block e^5 secured to the framework by a tongue and groove connection so as to be removable at will.

Means are also provided whereby the operating devices will be automatically connected and disconnected as the distributing mechanism is moved to and from its operative position. As shown in Fig. 2^a, such means comprise an arm K^6 fixed to the rock 60 shaft K^1 and having a laterally projecting

pin overlying the usual spring-pressed stop arm K^7 which is adapted to coöperate with a cam-shaped collar M^6 on the distributor clutch. When the hand lever K^2 is in its horizontal position with the distributing 70 mechanism lowered, the arm K^6 holds the stop arm K^7 out of engagement with the collar M^6 , but when the hand lever is depressed to raise the distributing mechanism the arm K^6 is consequently rocked upwardly 75 away from the stop arm K^7 , which under the influence of its spring, is then projected into the path of the rotating collar M^6 and effects the disengagement of the clutch in the usual way. Similarly, when the hand 80 lever is shifted in the opposite direction to restore the distributing mechanism to its normal position, the arm K^6 removes the stop arm K^7 from the collar M^6 and thus allows the clutch to be reengaged. Fig. 5

85 illustrates an alternative construction, wherein the connection and disconnection of the clutch is effected by means of a cam K^8 secured to the outer end of the shaft K^1 and coöoperating with the pivoted lever M^9 before 90 mentioned. This arrangement acts in the same way as the previous one, the shifting of the hand lever K^2 in opposite directions to raise and lower the distributing mechanism 95 effecting automatically the disengagement and engagement of the clutch, respectively. That is to say, when the hand lever K^2 is depressed to raise the distributing mechanism, the cam K^8 effects the rocking of the pivoted lever M^9 , which shifts the clutch 100 collar M^8 axially to break the engagement between the connecting elements M^5 , when the section M^3 is allowed to be disengaged from the rotating pulley M^2 . When subsequently 105 the hand lever is raised to restore the distributing mechanism to operative position, the cam K^8 rocks the lever M^9 in the opposite direction and brings the two connecting elements M^6 in engaging relation so that the section M^3 is again connected to the 110 rotating pulley M^2 . As before mentioned, the details of the clutch mechanism and their operation are fully set forth in the Rogers Patent No. 1,088,934.

115 It has before been explained that the channel entrances F are arranged to be swung downwardly from their operative position, but owing to their close arrangement to the distributing mechanism, it is desirable to prevent such swinging until the latter has been moved upward from its operative position. To this end, the shaft K^1 is provided at its inner end with a depending sector plate K^3 having an inwardly extending concentric flange K^4 adapted to engage behind a pin or roller F^3 secured to the side of the supporting frame F^1 . The circumferential extent of the flange K^4 is such that it maintains its engagement with the pin F^3 until the hand lever K^2 is shifted to 120 125 130

its extreme downward position, at which time the distributing mechanism is fully raised. In this position of the hand lever, the flange K^4 lies beyond the pin F^3 (see 5 Figs. 2 and 2^a), thus allowing the channel entrances to be swung downward as before described.

Similarly, in order to allow the closing 10 of the channel entrances F , the distributing mechanism should be raised, and for this reason, means are provided to prevent the lowering of the distributing mechanism until after the channel entrances have been returned to their normal or operative position. In the present instance, such means consist of a spring-pressed plunger L mounted in an arm L^1 projecting from the framework, the plunger being so located as to engage in a recess in the sector plate 20 K^3 when the latter is in its unlocking position, that is, when its flange K^4 is disengaged from the projecting pin F^3 of the channel entrance frame F^1 . Located in the recess in the sector plate is a short stud K^5 25 adapted to coöperate with the pin F^3 on the channel entrance frame. When the frame is in its closed position and the distributing mechanism is raised, the stud K^5 stands between and in alinement with 30 both the plunger L and the projecting pin F^3 , thus preventing the engagement of the plunger in the sector plate, but when the frame is swung downward it disengages the pin F^3 from the stud K^5 and thus allows the 35 locking plunger to enter the recess of the sector plate, pushing the stud before it. The stud is now projected beyond the operative face of the sector plate and stands in position to be engaged by the pin F^3 when 40 the frame F^1 is swung back to its operative position, thereby automatically disengaging the detent L from the recess of the sector plate. The effect of this arrangement is that the distributing mechanism is held in 45 its uppermost position by locking means which are automatically engaged and disengaged by the movement of the channel entrances from and to their normal or operative position, respectively.

50 Should it be desired for any reason to lower the distributing mechanism when the channel entrances are open, this may be done by withdrawing the plunger L by hand. However, since the distributing 55 mechanism, if left in its lowered position, would be struck by the channel entrances in their closing or return movement, means are provided to arrest or prevent such movement of the channel entrances while the distributing mechanism is in its operative position. As shown in Figs. 2 and 2^a, the sector plate K^3 , before referred to, is provided with a second concentric flange K^x 60 lying beyond the flange K^4 and of similar extent, so that when the flange K^4 is moved

to unlocking position by the raising of the distributing mechanism or so as to clear the pin F^3 on the channel entrance F^1 , the flange K^x will also clear the pin and thus allow the downward swinging of the frame. But 70 in any other position of the parts, the flange K^x will stand across the path of the pin F^3 and arrest the closing movement of the frame and thus prevent the engagement of the channel entrances with the distributing mechanism. It will be apparent that the flange K^x would perform its arresting function without regard to the use of the locking means for the distributor. 75

As previously stated, I have shown my 80 improvements only in preferred form and by way of example, and as applied to a linotype machine, but obviously many modifications and alterations therein and in their mode of application will suggest themselves 85 to those skilled in the art without departure from the scope of the invention.

Having thus described my invention, its construction and mode of operation, what I claim and desire to secure by Letters 90 Patent of the United States, is as follows:

1. In a typographical machine, the combination of distributing mechanism comprising a distributor bar and a set of conveying screws for propelling the matrices 95 therewith, a movable supporting frame carrying the whole of said distributing mechanism, and manually operable means for shifting the supporting frame to and from its operative position, the said means comprising a hand lever pivoted to the machine frame and a cam connected thereto and arranged in engagement with a part of the supporting frame. 100

2. In a typographical machine, the combination of a distributor mounted to move to and from operative position and including feed devices for propelling the matrices therewith, operating mechanism therefor, and automatic means for connecting 110 and disconnecting the operating mechanism as the distributor is moved to and from its operative position.

3. In a typographical machine, the combination of a distributor movable to and from operative position and including feed devices for propelling the matrices therewith, operating mechanism therefor comprising a clutch, and automatic means for opening and closing the clutch as the 120 distributor is moved from and to its operative position, respectively.

4. In a typographical machine, the combination of a distributor including feed devices for propelling the matrices therewith, operating mechanism therefor, a movable supporting frame for the distributor, a hand lever for shifting the supporting frame to and from its operative position, and connections from the hand lever to dis- 125 130

engage the operating mechanism when the supporting frame is shifted from its operative position.

5. In a typographical machine, the combination of a distributer including feed devices for propelling the matrices therethrough, operating mechanism therefor, a movable supporting frame for the distributer, a hand lever for shifting the supporting

10 frame to and from its operative position, and connections from the hand lever to engage and disengage the operating mechanism as the supporting frame is moved to and from its operative position.

15 6. In a typographical machine, the combination of a distributer, a channel entrance to receive the matrices therefrom, each of said parts being movable to and from its operative position, and locking means to prevent the movement of the channel entrance from its operative position, the said means being automatically released as the distributer is moved to its inoperative position.

20 7. In a typographical machine, the combination of a distributer, a channel entrance to receive the matrices therefrom, each of said parts being movable at will from its operative position, means for effecting such movement of the distributer, and locking means for holding the channel entrance against movement, the two said means being connected and related so as to insure the movement of the distributer prior to the 35 movement of the channel entrance.

8. In a typographical machine, the combination of a distributer, a channel entrance to receive the matrices therefrom, each of said parts being movable at will from its operative position, a hand lever for effecting the movement of the distributer, and locking means controlled by the hand lever for holding the channel entrance in its operative position.

45 9. In a typographical machine, the combination of a distributer, a channel entrance to receive the matrices therefrom, each of said parts being movable to and from its operative position, means for effecting the movement of the distributer, locking means for holding the channel entrance against movement, and a common operating device for the two said means acting to lock and unlock the channel entrance as the distributer is moved to and from its operative position.

10. In a typographical machine, the combination of a distributer, a channel entrance to receive the matrices therefrom, each of 60 said parts being movable to and from operative position, and means distinct from said parts to prevent the return of the magazine entrance to operative position when the distributer is in operative position.

65 11. In a typographical machine, the com-

bination of a distributer, a channel entrance to receive the matrices therefrom, each of said parts being movable to and from operative position, and means for arresting the channel entrance in its return to operative position, the said means being rendered active and inactive, respectively, as the distributer is moved to and from its operative position.

70 12. In a typographical machine, the combination of a distributer, a channel entrance to receive the matrices therefrom, each of said parts being movable to and from operative position, locking means to hold the distributer in its inoperative position, and means whereby the movement of the channel entrances to operative position disengages said locking means.

75 13. In a typographical machine, the combination with a distributer and a channel entrance to receive the matrices therefrom, each of said parts being movable to and from operative position, of means to insure the return of the channel entrance to operative position before the distributer is moved back to its operative position.

80 14. In a typographical machine, the combination with a distributer and a channel entrance to receive the matrices therefrom, each of said parts being movable to and from its operative position, of locking means to hold the distributer in its inoperative position, and means whereby said locking means are rendered active and inactive as the channel entrance is moved from and to its operative position, respectively.

85 15. In a typographical machine, the combination of the magazine entrance F, the rotary sector plate F³ for holding it in operative position and provided with the stud K³, and the spring pressed plunger L mounted in the framework of the machine and adapted to aline with the stud when the sector plate is moved to unlocking position.

90 16. In a typographical machine, the combination of a plurality of distributers, a font separator therefor, and a plurality of tubes leading therefrom to the respective distributers, the said tubes being mounted to rock or tilt about a horizontal axis, for the purpose described.

110 17. In a typographical machine, the combination of a plurality of distributers, a font separator therefor, a plurality of tubes leading therefrom to the respective distributers, and a support whereon the tubes are mounted to rock or tilt about a horizontal axis, the said support being detachably connected to the framework of the machine so as to permit the removal of the tubes at will.

120 18. In a typographical machine, the combination of a plurality of distributers movable at will from their operative position, a font separator, a plurality of tubes leading therefrom to the respective distributers and

mounted to rock or tilt about a horizontal axis, and automatic means for effecting the rocking of the tubes as the distributers are moved.

5 19. In a typographical machine, the combination of a plurality of distributers movable at will from their operative position, a font separator, a plurality of tubes leading therefrom to the respective distributers and 10 mounted to rock or tilt about a horizontal axis, and common means for effecting the movement of the distributers and the rocking of the tubes.

20. In a typographical machine, the combination of a plurality of distributers movable at will from their operative position, a font separator, a plurality of tubes leading therefrom to the respective distributers and mounted to rock or tilt about a horizontal 15 axis, and means to prevent the movement of the distributers until the tubes have been rocked from their operative position.

21. In a typographical machine, the combination of a plurality of distributers movable at will from their operative position, a font separator, a plurality of tubes leading therefrom to the respective distributers and mounted to rock or tilt about a horizontal 25 axis, and locking means for holding the distributers against movement, said locking means being released by the rocking of the tubes.

22. In a typographical machine, the combination of a plurality of distributers movable at will from their operative position, a font separator, a plurality of tubes leading therefrom to the respective distributers and mounted to rock or tilt about a horizontal 35 axis, means for effecting the movement of the distributers, means for effecting the tilting of the tubes, and a common operating device for both said means.

23. In a typographical machine, the combination of a plurality of distributers movable at will from their operative position, a font separator, a plurality of tubes leading therefrom to the respective distributers and mounted to rock or tilt about a horizontal 45 axis, manually operable means for effecting the movement of the distributers, and connections whereby the initial operation of said means effects the rocking or tilting of the tubes.

24. In a typographical machine, the combination of a plurality of distributers, a font separator, a plurality of tubes leading therefrom to the respective distributers, and means for moving the tubes from their operative position, the said means being constructed to yield in the event of undue resistance offered to the movement of the tubes.

25. In a typographical machine, the com-

bination with a distributer and a channel entrance to receive the matrices therefrom, each of said parts being movable to and from operative position, of means distinct from said parts to prevent the movement of the channel entrance from its operative position until the distributer has been moved from its operative position.

26. In a typographical machine, the combination of a plurality of distributers movable at will from their operative position, a font separator, connecting tubes leading from the separator to the respective distributers and arranged to be moved out of operative relation thereto, and common means for effecting the movement of the distributers and connecting tubes, the said means being constructed to initiate the movement of the tubes slightly in advance of that of the distributers, for the purpose described.

27. In a typographical machine, the combination of a plurality of distributers movable at will from their operative position, a font separator, connecting tubes leading from the separator to the respective distributers and arranged to be moved out of operative relation thereto, common means for effecting the movement of the distributers and the connecting tubes and constructed to initiate the movement of the tubes slightly in advance of that of the distributers, and locking devices, adapted to be released by the preliminary movement of the tubes, for holding the distributers against movement.

28. In a typographical machine, the combination of a plurality of distributers movable at will from their operative position, a font separator, connecting tubes leading from the separator to the respective distributers and arranged to be moved out of operative 100 relation thereto during the movement of the distributers, and means to insure the movement of the connecting tubes slightly in advance of that of the distributers, for the purpose described.

29. In a typographical machine, the combination of a plurality of distributers movable at will from their operative position, a font separator, connecting tubes leading from the separator to the respective distributers and arranged to be moved out of operative relation thereto, means for effecting the movement of the distributers, and connections whereby the initial operation of said means effects the movement of the 115 connecting tubes without imparting movement to the distributers.

In testimony whereof, I have affixed my signature.

DAVID S. KENNEDY.
